[57] CLAIM

The ornamental design for a tape playback device, as shown and described.

DESCRIPTION

FIG. 1 is a perspective view of the tape playback device embodying the design of the present invention;
FIG. 2 is a top plan view thereof;
FIG. 3 is a bottom view thereof;
FIG. 4 is an end elevational view thereof, the end opposite being a mirror image of the end shown in FIG. 4;
and,
FIG. 5 is a rear elevational view thereof.
